UNITED STATES PATENT OFFICE

WILLIAM L. HANAVAN, OF MONTCLAIR, NEW JERSEY

RECEPTACLE AND CLOSURE THEREFOR

Application filed July 10, 1931. Serial No. 549,892.

This invention relates to a receptacle and closure therefor.

The invention relates more particularly to the shipment of materials, such as cement, in bulk in large containers. After these containers reach their destination they are lifted, inverted and dumped and often the cement is scattered in the air or by the wind. This is obviously wasteful and is also injurious to the surface on which the cement settles.

This invention has for its salient object to provide a shipping receptacle with a closure that can be easily and quickly secured over the open end of the receptacle and which will act as a shielding or guiding chute when the receptacle is dumped.

Another object of the invention is to provide a receptacle with a closure so constructed and arranged that it can be easily and quickly secured over the open end and furthermore can be readily released when the receptacle is to be dumped.

Further objects of the invention will appear from the following specification taken in connection with the drawing which forms a part of this application, and in which

Fig. 1 is a perspective view of a receptacle and closure constructed in accordance with the invention;

Fig. 2 is an elevational view taken at right angles to Fig. 1;

Fig. 3 is an elevational view partly in section and at right angles to Fig. 2;

Fig. 4 is an enlarged sectional elevation showing the means for securing the closure to the receptacle; and

Fig. 5 is a detail sectional elevation showing one of the bolts to which the clamping bar for the end of the closure is secured.

The invention briefly described consists of a receptacle which may be of any desired form or shape and has one end, preferably the upper end, open. The receptacle is preferably provided with trunnions on which it may be tilted.

The open end of the receptacle is closed by a flexible sheet of material, preferably water proof, such as a canvas sheet. The sheet is wrapped around the receptacle and is then folded inwardly, the upper end thereof being folded downwardly across the top of the receptacle and over one edge thereof. The free end of the closure is secured in any desired manner, as by a clamping bar. When the receptacle is to be dumped this bar is removed and the receptacle is tilted whereupon the material in the receptacle will be discharged, the flexible sheet acting during this operation as a shield or chute to prevent the material from blowing or being scattered in the air.

Further details of the invention will appear from the following description.

In the embodiment of the invention shown in the drawing there is illustrated a receptacle 10 which may be of any desired form or shape and is preferably constructed of steel. The receptacle 10 is provided with trunnions 11 which are disposed below the center of gravity of the receptacle when the receptacle is loaded and supported on its base.

The upper outer edge of the receptacle has formed thereon or secured thereto a ring 12. The closure for the receptacle consists of a sheet 13 of material, preferably water proof material, such as canvas or duck. The sheet 13 is wrapped around the upper edge portion of the receptacle, the edges preferably being overlapped, as shown in dotted lines in Fig. 1 and the overlapping edges may, if desired, be stitched.

A rope or cord 15 is secured to the inner surface of the flexible sheet at a point spaced from the upper end thereof and a similar cord 16 is secured to the outer surface. These cords are so spaced as to dispose them on opposite edges of a clamping strap 20 which may, if desired, be formed in two or four parts, the adjacent sections being provided with flanges 21 by which the sections can be secured together. This arrangement is par-

ticularly shown in Fig. 4 wherein it will be seen that the rope 15 is disposed beneath the ring 12 and above the clamping strap or straps 20 and the rope 16 is disposed below the clamping strap or straps.

After the sheet has been secured around the upper edge portion of the receptacle in the manner described it is drawn upwardly and folded inwardly, as shown in Fig. 1, the 10 free end of the folded sheet being carried downwardly over one edge of the receptacle and clamped beneath a bar 25 which is carried by bolts 26.

When the receptacle is to be dumped, hooks 15 27 carried by a yoke 28 are lowered into engagement with the trunnions 11 and the receptacle is then raised. The tilting of the receptacle on the trunnions is normally prevented by a latch member 30 which normally 20 engages a lug 31 carried by the receptacle, the latch being mounted on one of the hooks 27. When the receptacle has been swung to the position in which the contents are to be dumped and the bar 25 has been removed, the 25 latch 30 will be released and the receptacle will be inverted, the contents being discharged downwardly through the flexible sheet of material, which in this operation, functions as a guiding chute.

30 From the foregoing description it will be seen that simple and practical closure means has been designed for closing a shipping receptacle and that the closure when released will act as a chute to prevent the material 35 from being scattered.

Although one specific embodiment of the invention has been particularly shown and described, it will be understood that the invention is capable of modification and that 40 changes in the construction and in the arrangement of the various cooperating parts may be made without departing from the spirit or scope of the invention, as expressed in the following claims.

45 What I claim is:

1. A receptacle, having a single open side a closure therefor comprising a flexible member secured around the edge portion of said open side of the receptacle to form a continuation 50 of the walls of the receptacle, and folded across said open side of the receptacle, and means securing the folded member across said open side.

55 2. A receptacle, having a single open side a closure therefor comprising a flexible member secured around the edge portion of said open side of the receptacle to form a continuation of the walls of the receptacle, and folded across said open side of the receptacle, and means on the outer surface of the receptacle and adjacent an edge of the open side securing the folded member across said open side.

60 3. A receptacle, having a single open side and a closure therefor comprising a flexible sheet secured around the receptacle to form

a continuation of the walls thereof and secured thereto over the open side, said folded sheet having the portion above the open side of the receptacle folded together and downwardly across the opening of the receptacle, 70 and means engaging and securing the projecting end portion of said folded cover to a wall of the receptacle.

4. A receptacle, having a single open side and a portion extending laterally from the upper end, a closure for the open side of the receptacle comprising a sheet of flexible material extending around the open side and forming a continuation of the walls of the receptacle, said closure having a member secured thereto and disposed below said laterally extending portion of the receptacle, means for securing the closure around the receptacle, and means for securing the sheet across the open side of the receptacle. 80 85

5. A receptacle having an open upper end and a portion extending laterally from the upper end, a closure for the receptacle comprising a chute of flexible material extending around the upper end and having a cord secured thereto and disposed below said laterally extending portion of the receptacle, means for securing the closure around the receptacle, and means for securing the chute across 90 the open end of the receptacle. 95

6. A receptacle having an open upper end, a closure comprising a sheet of flexible material folded around the upper end portion of the receptacle, clamping means extending around the receptacle and closure sheet for securing the sheet, and means carried by the sheet and disposed below said clamping means for preventing upward displacement of the sheet. 100

7. A receptacle having an open upper end and an external flange on the upper edge, a sheet of flexible material folded around the upper end portion of the receptacle, a clamp disposed below the flange and securing the sheet, and means carried by the sheet and disposed below the flange and below the clamp for preventing upward displacement of the sheet. 105 110

8. A receptacle having an open upper end and an external flange on the upper edge, a sheet of flexible material folded around the upper end portion of the receptacle, a clamp disposed below the flange and securing the sheet, means carried by the sheet and disposed below the flange and below the clamp for preventing upward displacement of the sheet, and means for securing the folded closure sheet over the open end of the receptacle. 115

9. A receptacle having an open upper end and an external flange on the upper edge, a sheet of flexible material folded around the upper end portion of the receptacle, the longitudinal edges of the sheet being overlapped, a clamp disposed below the flange and securing the sheet, and means carried by the sheet 120 125 130

and disposed below the flange and below the clamp for preventing upward displacement of the sheet.

10. A receptacle, having a single open side, 5 a closure therefor comprising a flexible member secured around the edge portion of said open side of the receptacle to form a continuation of the walls of the receptacle, and folded across said open side of the receptacle, and 10 means securing the folded member across said open side, the longitudinal edges of the sheet being overlapped.
